(57) **CLAIM**

The ornamental design for a ground stab alignment bracket for a motor control center, as shown and described.

DESCRIPTION

FIG. 1 is a perspective view of a ground stab alignment bracket for a motor control center showing my new design;

FIG. 2 is a front view thereof;

FIG. 3 is a rear view thereof;

FIG. 4 is a top plan view thereof, the bottom plan being a

mirror image; and,

FIG. 5 is a left side view thereof, the right side view being a

mirror image.

The broken lines shown represent unclaimed subject matter

and form no part of the claimed design.
